HANDLING-GEAR FOR INTERNAL-COMBUSTION ENGINES.

1,247,647.

Specification of Letters Patent.

Patented Nov. 27, 1917.

Application filed March 29, 1916. Serial No. 85,287.

To all whom it may concern:

Be it known that we, GREGORY C. DAVISON and JOHN W. ANDERSON, citizens of the United States, and residents of New London, in the county of New London and State of Connecticut, respectively, have invented certain new and useful Improvements in Handling-Gears for Internal-Combustion Engines; and we do hereby declare the following to be a full, clear, and exact description of the invention, such as will enable others skilled in the art to which it appertains to make and use the same.

This invention relates to internal combustion engines and involves the provision of a novel form of control mechanism such that by the operation of this mechanism an inexperienced or careless operator can hardly fail to start and run the engine properly in one direction or the other as desired and with complete insurance against danger due to those irregularities of fuel supply, sudden strain upon the engine parts, and other accidents possible in all installations as constructed in the manner heretofore common.

In accordance with one feature of the invention relating to the starting of the engine in operation, the several cylinders of the engine are divided into two or more groups, and in starting, compressed air is first admitted to the cylinders of one group, and if that does not suffice to start the engine in operation, the compressed air is admitted to the cylinders of a second or even a third group until operation of the engine is effected. The fuel is admitted to the cylinders to which compressed air is not being admitted and ignition of the fuel is effected so as to continue the operation of the engine by means of the combustion of the fuel in the usual manner. With the engine operating in this way, the several cylinders or groups of cylinders, which have been connected to the compressed air supply, are successively disconnected therefrom and fuel is admitted to them until finally fuel is being admitted to all of the cylinders and ignited therein for operation of the engine in the usual manner. To simplify the operation of starting a reversible engine thus, a controller is provided having an operating handle which may be moved either way from a central position and which when moved to

one side effects operation of the engine in one direction and when moved to the other side effects operation of the engine in the reverse direction. The movement of the controller handle in one direction may be arranged to admit compressed air to the cylinders of one group while disconnecting those cylinders from the fuel supply, and continued movement of the controller handle may admit compressed air to a second and, if desired, a third group of cylinders, the fuel supply being disconnected from any cylinder to which compressed air for starting is admitted. When operation of the engine has been thus effected, the controller handle may be moved back to disconnect the cylinders from the compressed air supply until finally the supply of compressed air for starting the engine is entirely discontinued and the engine is operated by the admission of fuel to all of the cylinders.

The invention is specially applicable to engines of the type in which heavy oil is used as the fuel and it involves the provision of improved means for regulating and controlling the supply of the fuel oil to the cylinders. Each cylinder is provided with an inlet valve to which compressed air and fuel oil are admitted in regulated quantities and each valve is operated mechanically in accordance with the rotation of the engine shaft to admit a charge to the cylinders. When the valve is opened, the compressed air passes therethrough to the engine and the oil is forced under pressure into the moving body of air and is taken up thereby in the form of a multiplicity of minute particles. We have found that in the operation of heavy oil engines, it is of great importance that in regulating the fuel charges both the compressed air and the oil fuel delivered to the inlet valve should be regulated together so that they will always have a certain relation which has been ascertained to be conducive of the best results. An apparatus constructed in accordance with the invention therefore embodies a mechanism for supplying a fuel charge to each cylinder, a single control device for all of said mechanisms and means operated by the control device, whereby simultaneous adjustment is effected of the freedom of flow of compressed air to the inlet valves and

also of the amount of fuel oil supplied to the inlet valves for each operation thereof.

When starting the engine in operation, preferably in the manner above outlined, it is important that the fuel should not be admitted to the cylinders to which compressed air is being admitted through the starting valves. Otherwise, not only would waste of fuel result, but also such procedure would involve certain dangers to the apparatus which should be avoided. Therefore, in accordance with another feature of the invention, means are provided whereby, when compressed air is admitted to certain cylinders through the starting valves thereof, the fuel-inlet valves are rendered inoperative to supply fuel to those cylinders through the inlet valves thereof. This may be conveniently effected pneumatically by causing the compressed air which brings the starting valves into operation to render inoperative the pumps for pumping oil to the inlet valves of the corresponding cylinders.

The invention also involves the provision of certain interlocks for guarding against improper operation of the mechanism such as might result in injury to the apparatus. The controller for regulating the charges of fuel supplied to the cylinders is arranged adjacent to the controller for operating the compressed air starting devices and interlocking devices are provided between them such that the controller for the fuel cannot be operated when the controller for the compressed air starting devices is in the intermediate position at which time the cylinders of the engine are vented, and such that when the controller for the fuel is in a position for admitting fuel to the cylinders, the controller for the compressed air starting devices cannot be moved to the mid position in which the cylinders are vented. Means are also provided for preventing movement of certain of the controlling devices too rapidly from a position for running the engine in one direction to a position for running the engine in the opposite direction, so as to insure that the engine has come to rest completely before compressed air is admitted to any cylinders for starting the engine in the opposite direction.

These and other features of the invention will be better understood by reference to the following description in connection with the accompanying drawings which show the preferred embodiment of the invention.

In the drawings, Figure 1 is a diagrammatic view showing an application of the invention to a six-cylinder reversible engine having two three-cylinder separately controllable operating units;

Fig. 2 is a sectional view of the control box taken on the line 2-2 of Fig. 1;

Fig. 3 is a diagrammatic view, showing a variation of the control-box of Fig. 1;

Fig. 4 is a sectional view taken on the line 4-4 of Fig. 3;

Fig. 5 is a view similar to Fig. 4, showing a further modification;

Fig. 6 is a diagrammatic view showing the elementary disclosure of Fig. 1 amplified for practical installation in connection with the engine mentioned;

Fig. 7 is an enlarged detail view, showing in bottom plan certain of the parts of Fig. 6;

Fig. 8 is a sectional detail view of one of the interlock devices for the larger hand wheel;

Figs. 9 to 15 inclusive are each a diagrammatic showing of related settings of the six control valves of Fig. 1;

Fig. 16 is an enlarged sectional detail view, taken on the line 16-16 of Fig. 6;

Fig. 17 is a sectional detail view taken on the line 17-17 of Fig. 16; and

Fig. 18 is a generally schematic view showing another embodiment of the invention.

Referring to Fig. 1, a six-cylinder marine engine, the cylinders of which are divided into two groups as indicated at A and B, is shown as associated with a pneumatic control-box 7.

The control-box is equipped with three pairs of control valves, the members of one pair being marked 1 and 2, the members of a second pair being marked 3 and 4, and the members of a third pair being marked 5 and 6. Air is fed to and adapted to be fed through any of these control valves by means of a conduit 8.

Leading from valve 1 is a connection 11 for actuating any suitable type of ahead-setting-means for the air-starting valves of the B-group of cylinders; leading from valve 2 is a connection 12 for actuating the ahead-setting-means for the air-starting valve of the A-group of cylinders; leading from valve 3 is a connection 13 for actuating the astern-setting-means for the air-starting valves of the B-group, and leading from valve 4 is a connection 14 for actuating the astern-setting-means for the air-starting valves for the A-group.

Thus, either the A or the B-group of cylinders may first be set for ahead or astern running and thereafter the air-starting valves of the other group may be set for similar running, or else all cylinders may be initially set for such running and then one group may have its air starting valves rendered inoperative. Assume that it is the B-group of cylinders whose air-starting valves are in the inoperative position. Oil-fuel and spray-air may be fed to the cylinders of the B-group, by any familiar means not here illustrated, while the pistons of those cylinders are reciprocating due to the admission of compressed air to the cylinders of the A-group. In this case combustion of

the heavy oil-fuel fed to the B-group promptly occurs, whereupon the engine shaft (not shown) becomes driven as well by the pistons of the B-group and the cylinders of the A-group may as a final operation be disconnected from the air supply and connected to the fuel.

The four controlling valves 1, 2, 3 and 4 do not directly admit compressed air to the cylinders for starting the engine; as above explained, the four valves merely control the setting of the air-starting valves so as to render them inoperative, or to set them for running the engine ahead, or to set them for running the engine astern. The construction employed in each of the air-starting valves whereby it may thus be selectively arranged is well known in the art. When any one of the control valves 1, 2, 3, and 4 is actuated to move the corresponding air-starting valves on the cylinders to one of their operative positions, the control valve 5 is opened. Thereupon air from conduit 8 flows through a connection 15, relay valve 15^a is actuated, and a compressed air conduit 15^b is opened so that compressed air flows to the air-starting valves of the several cylinders and enters the cylinders whose valves have been set to admit it.

30 The sixth control valve 6 is provided for venting the cylinders when desired. A connection 16 leads from valve 6 and is adapted to convey air to open suitably designed relief valves one on each cylinder.

35 A convenient structure for the control-box 7, and for a means adapted to actuate the various control valves as above described, is indicated in Fig. 2. The conduit 8 communicates with the main passage 7' which is provided with branch passages leading to each of the six control valves. The right branch passage of Fig. 2 leads to control valve 2 and the left branch passage of said Fig. 2 leads to control valve 1. The construction 40 of this valve 1 is similar to that of all the other control valves, and includes a valve cup 1^a spring-held against its seat 1^b, a passage 1^c within which may reciprocate a plunger 1^d, a passage leading from passage 1^e and communicating with connection 11, and a vent passage 1^f normally maintaining communication between the outside air and the interior of passage 1^c. Upon pushing upward plunger 1^d sufficiently to lift the 45 valve-cup off its seat and thus permit compressed air to enter passage 1^c for flow into connection 11, the main body of the plunger 1^d closes vent passage 1^f. Upon the release of plunger 1^d, the compressed air in main 50 passage 7', together with the spring actuating the valve 1^a, force the valve downwardly upon its seat. Also, the plunger 1^d drops downward as the bell-crank 10 turns on its pivot and opens the vent passage 1^f to 55 permit escape to the atmosphere of the com-

pressed air in the connection 11. A similar construction may be characteristic of valves 3 and 4 and also of valves 5 and 6.

The six control valves may be manually selectively actuated, for operation as just described, by means of a suitable handle fixed upon a shaft 8' arranged below main passage 7' and extending parallel therewith. On this shaft 8' are a plurality of cams 9 each adapted to actuate a pivoted bell-crank 75 lever 10 or 10^a and thus operate the corresponding plunger 1^d whose lower end rests upon the upper surface of the bell-crank, it being understood that the bell-cranks 10 for the control valves 1, 3 and 5 extend to one 80 side of shaft 8' and the bell-cranks 10^a for the control valves 2, 4 and 6 extend to the opposite side. The handle on shaft 8' thus constitutes a single controller whereby the A-group or B-group of cylinders or both 85 groups may be set for astern or ahead running on air as and when desired.

The means shown in Fig. 2 for venting a control valve is not as economical of air as either of the means shown in Figs. 4 and 5. 90 In order more clearly to understand the construction of Figs. 4 and 5, assume that there is substituted in Fig. 1 the control-box 7 of Fig. 3, in which each control valve 1, 2, 3, 4, 5 and 6 has its own separate vent valve 1^f, 95 1^f, 4^f, 5^f and 6^f arranged opposite it at the other side of the control box.

In the construction shown in Fig. 4, a spring-closed valve disk 1^g is interposed between main passage 7' and connection 11, 100 and a spring-closed valve disk 1^h is interposed between the vent passages 1^k and 1^m. Each disk may be elevated above its seat by means of its depending plunger actuated from shaft 8' by cams 9 and 9' and bell-cranks 10 and 10'. After shaft 8' has been rotated in the direction of the arrow to raise disk 1^g and admit air to connection 11, a further rotation of the shaft in the same direction permits the disk 1^g to close against 110 its seat and raises disk 1^h from its seat, thereby shutting off the air-flow to connection 11 and venting said connection by way of passages 1^k and 1^m.

Fig. 5 illustrates a self-explanatory variation of the construction shown in Fig. 4, wherein but a single cam 9'' and a single lever 10'' are employed in connection with the control valve for connection 11. Spring 17 holds the lever in engagement with the 120 cam. Such a construction, also, may be employed for all of the six control valves.

Referring next to Figs. 6 and 7, these figures show the A-cylinders, the B-cylinders, control-box 7, control-valves 1, 2, 3, 125 4, 5 and 6, connections 11, 12, 13, 14, 15 and 16, conduit 8, relay valve 15^a, and air-starting conduit 15^b. To simplify the illustration, the control-box 7 is like that shown in Fig. 1, not like that shown in Fig. 3, and 130

the control valve construction is similar to that described in connection with Fig. 2. Each plunger (marked respectively 1^z, 2^z, 3^z, 4^z, 5^z, and 6^z in Fig. 7) is adapted to operate a valve so as to close or open communication from the compressed air supply pipe 8' to one of the branch pipes 11, 13, 15, 12, 14 and 16.

Fig. 7 shows the under side of the control-box, bell-cranks 10 and 10^a for actuating the control valves, and cams 9 and 9^a for actuating the bell-cranks. These bell-cranks are pivotally hung from a rod parallel and in the same vertical plane with shaft 8', but spaced above the latter and below the bottom of the control-box. This rod is not shown in Fig. 7, but is illustrated at 22 in Figs. 2, 9 and 13. Shaft 8' is a tubular shaft journaled in brackets 18. This shaft 20 is thus constructed so that there may be arranged concentrically therewith a solid shaft 20, carrying a fuel hand-wheel 21 and other parts hereinafter described.

The shaft 8' carries fixedly a main hand-wheel 19 for rotating the hollow shaft to set the control valves as illustrated in any of Figs. 9 and 15. Referring now to these Figs. 9 to 15, wherein it should be noted, the shaft 8' is for greater clearness shown solid, each of these figures includes three sectional diagrams, one diagram for the pair of control valves 1 and 2, one for the pair 3 and 4 and one for the pair 5 and 6.

The main hand-wheel 19 may be set to 35 arrange the six cams on shaft 8' as shown in Fig. 9, and then an index 19^x (Fig. 6) carried by the hand-wheel lies opposite a "stop" indicium on a suitable scale (not shown) carried by the outer face of a fixed 40 frame 23 (Fig. 7). In this position of the hand-wheel, all the control valves are closed except control valve 6 which when opened vents all the cylinders.

Assuming that the engine is to be run 45 ahead, the main hand-wheel 19 is turned in a counter-clockwise direction through an angle of about 30° until the index 19^x lies opposite a suitable "first ahead" indicium on the fixed frame 23, and the parts of the controller are brought to the positions indicated 50 in Fig. 10. Then all the control valves are closed including the vent valve 6 shown open in Fig. 9. When the main hand-wheel is turned approximately 30° farther in a 55 counter-clockwise direction, as shown in Fig. 11, the index 19^x lies opposite a suitable "second ahead" indicium on the fixed frame 23 and then all the control valves are closed except control valves 2 and 5. The 60 opening of valve 2 causes a setting of the air-starting valves of the A-cylinders for running the engine ahead on air, and the opening of valve 5 actuates relay valve 15^a so that starting-air is fed to those air-starting 65 valves. This may suffice to start the

engine. If it does not, the main hand-wheel 19 is turned approximately 30° farther in a counter-clockwise direction, carrying the parts to the positions shown in Fig. 12 in which the index 19^x lies opposite a suitable "third ahead" indicium on the fixed frame 23. Then both control valves 1 and 2 are open and the opening of the valve 1 causes a setting of the air-starting valves of the B-cylinders for running those cylinders ahead on air. In this position, the control valve 5 is open so that compressed air passes through valve 15^a to the starting valves of all the cylinders and control valves 1 and 2 are both open so that the starting valves of all cylinders are set for the admission of air at the appropriate times for running the engine ahead.

Assume now that the engine is to be run astern, Figs. 13 to 15 showing shaft 8' rotated different fractional amounts in a clockwise direction from its "stop" adjustment of Fig. 9, should be examined; Fig. 13 showing a shaft rotation of approximately 30°, Fig. 14 showing a shaft rotation of approximately 60°, and Fig. 15 showing a shaft rotation of approximately 90°. When main hand-wheel 19 is set to arrange the six cams on shaft 8' as disclosed in Fig. 13, index 19^x lies opposite a suitable "first astern" indicium on the fixed frame 23; and the cylinder vent-valves are closed since all the control valves are closed. When the main hand-wheel is set to arrange the six cams as disclosed in Fig. 14, said index 19^x lies opposite a suitable "second astern" indicium on the fixed frame 23; and then all the control valves are closed except valves 4 and 5, the opening of valve 4 as aforesaid causing a setting of the air-starting valves of the A-cylinders for running those cylinders astern on air, and the opening of valve 5 as aforesaid actuating the relay valve 15^a so that starting-air is fed to such air-starting valves. Thereupon the engine may or may not start. If not, the main hand-wheel is set to arrange the six cams as disclosed in Fig. 15 and said index 19^x lies opposite a suitable "third astern" indicium on the fixed frame 23; and then the control valve 3 will also open, the opening of this valve as aforesaid causing a setting of the air-starting valves of the B-cylinders for running those cylinders astern on air, the previously opened control valve 5 having already actuated relay valve 15^a so that starting-air will now be fed to all the air-starting valves, whereupon the engine will immediately start.

After the engine is under way with all of the cylinders operating on compressed air, the hand wheel of the controller is moved back from the "third ahead" position to the "second ahead" position illustrated in Fig. 11, thus discontinuing the operation of the

air-starting valves of the cylinders of one group, and oil fuel is admitted to the cylinders of that group by the devices herein-after described so that then the engine will operate with compressed air in three cylinders and the admission and combustion of fuel in the other three cylinders. Then the hand-wheel of the controller is moved back to the "first ahead" position shown in Fig. 10, thereby discontinuing the operation of the air-starting valves of the second group of cylinders, and fuel is admitted to those cylinders for operation in the usual manner. The position of the parts indicated in Fig. 10 is the running position.

When it is desired to discontinue the operation of the engine, the hand-wheel of the controller is moved from the Fig. 10 position to the Fig. 9 position, in which position all of the air-starting valves are inoperative and all of the cylinders are vented to the atmosphere by reason of the operation of valve 6.

To operate the engine in the reverse direction, the hand-wheel is moved in the opposite or clockwise direction to a first, (Fig. 13) a second (Fig. 14) and a third (Fig. 15) position, each step movement being approximately 30° in extent, and in each of these first, second and third astern positions the operation of the engine is the same as that described above, except that the engine runs in the reverse direction. In starting the engine in the astern direction the hand-wheel is first moved to the position indicated by Fig. 14 in which compressed air is admitted to the cylinders of one group. If necessary, the wheel can be moved to the third reverse position in which case starting air will be admitted to the cylinders of both groups. After the engine has been started in this way, the hand wheel may be moved back to the Fig. 14 position and fuel admitted to the cylinders of one group, and thereafter the hand wheel may be moved to the Fig. 13 position which is the running position and in which the starting air is not supplied to any of the cylinders and oil fuel is supplied to all of them.

Thus, no matter whether the engine has been running ahead or astern, on air or fuel or both, and it is desired to run the engine in the opposite direction, in giving the hand wheel 19 the rotation necessary to attain this end the index 19^x must first be brought to and past the stop indicium on frame 23, with the result that all cylinders must be vented as a preliminary to running the engine in the opposite direction. If such venting of the cylinders were not thus automatically provided for, a dangerous situation would result and explosions would be liable to occur in the cylinders to which starting air was subsequently introduced.

In order to insure that a careless operator will not rotate the hand wheel 19 past the mid-position too rapidly in either direction, locking devices are provided which arrest the movement of the hand wheel temporarily in the mid-position, in which position the cylinders of the engine are vented to the atmosphere. These locking devices are illustrated in Figs. 6, 7 and 8. The conduit 16 leading from the control valve 6 to the several cylinders is provided with a branch pipe 16^a leading to the cylinders of two locking devices 16^b, the construction of which is illustrated in Fig. 8. Each locking device includes a pin 16^c carried by a piston which moves in a small cylinder, the pin being normally held retracted by a spring 16^d. The pin may be projected by air admitted to the inner side of the piston through the branch pipe 16^a, and when the pin is so projected it lies in the path of movement of a projection 19^e carried by the hand wheel 19.

When the engine is running in one direction and it is desired to reverse the direction of its operation the supply of fuel to the cylinders is discontinued and the handle 19 is moved to the mid-position in which all of the cylinders are vented to the atmosphere. The movement of handle 19 is then continued past the mid-position to the positions described above for starting and running the engine in the reverse direction.

As the hand wheel 19 is so moved to the mid-position, it operates the valve 6 as above described to admit air under pressure to the pipe 16. Some of this air flows through the branch pipe 16^a to the cylinders of the locking devices 16^b so that those devices are projected into the path of movement of the projection 19^e on the hand wheel. Therefore, if a careless operator attempts to move the hand wheel 19 too rapidly past the mid-position so that the cylinders would not be properly vented before the parts were placed in the positions for operating the engine in the reverse direction, the projection 19^e on the hand wheel would come into engagement with one of the projections 16^c of the locking devices 16^b and would be arrested thereby.

After the cylinders have been vented and the hand wheel is moved slightly past the mid-position, the air admitted to the pipe 16 and branch pipe 16^a escapes through the exhaust port 6^e shown in Fig. 9, and thus permits the locking pins 16^c to be retracted by their springs 16^d. These locking devices, therefore, require but a momentary pause in the mid-position before proceeding to turn the hand wheel to the positions appropriate for starting the engine in the reverse direction, but they guard effectually against a too rapid and continuous movement of the hand wheel from one

of the positions for operating the engine in one direction to one of the positions for operating the engine in the reverse direction. As there are two locking devices provided, one on either side of the projection 19', when the hand wheel is in the mid-position too rapid movement of the hand wheel past the mid-position in either direction is prevented.

10 The organization so far described explains the features of the invention involving the cylinder-group control and the control of the devices for starting the engine in operation either astern or ahead and for 15 reversing.

15 As soon as the engine has started in operation in either direction so that only one group of its cylinders is running on air, it is intended to feed fuel, that is oil and 20 spray-air, to the fuel-spray valves of the cylinders of the other group, whereby this latter group may run on fuel and thus take up the work of driving the engine shaft and permit the first group to be taken off 25 air and put on fuel.

20 In describing the means shown for attaining these ends, reference will now be had to Figs. 6, 7, 16 and 17.

25 The solid shaft 20, which fixedly carries 30 fuel hand wheel 21 and which is rotatable as explained within and independently of hollow shaft 8' (Fig. 7), extends beneath the control-box 7 and the bank of engine cylinders as indicated in Fig. 6, and also 35 fixedly carries a gear segment 25 (Fig. 16). With the parts arranged as shown in Fig. 16, and with the hand wheel 21 set as shown in Fig. 7, a needle-valve 26 is closed. This needle-valve is interposed between the connections 27 and 28 of the spray-air line as 40 shown in Fig. 6, the connection 28 leading from a suitable source of compressed air supply and the connection 27 leading to the fuel-spray valves of all the cylinders. Referring again to Fig. 16, the needle-valve 45 is carried by the upper end of a vertical shaft 26' which is threaded in a member 29 of the valve casing so that turning shaft 26' effects an adjustment of the opening and 50 closing of the valve. The lower portion of the shaft 26' is splined within a hollow shaft 30 journaled in a bearing 31 and carrying at its lower end a beveled pinion 32 which meshes with gear segment 25. When 55 fuel hand-wheel 21 is rotated to turn shaft 20 and gear segment 25 in the direction of the arrow 25' on Fig. 16, the valve-stem 26' is rotated and the threads thereon cause the valve to be moved gradually to the 60 closed position.

While a common needle-valve is provided for adjusting the spray-air for all the cylinders, the oil-fuel for each cylinder is fed by its own fuel-pump A' or B', and the 65 plunger of each pump is reciprocated by

means carried by an auxiliary shaft 33 (Fig. 6). This shaft is geared in any suitable manner (not shown) to the engine shaft for revolution therewith. Oil-fuel is delivered to each pump by means of a common feed connection 37 leading from a suitable tank (not shown), and the pumped fuel is led from each pump to the corresponding cylinder by means of an individual connection 38. The pumps are all similar and simultaneously controlled, and one thereof is illustrated in section in Fig. 16. This pump includes a plunger 34, pivoted to and driven by an arm depending from an eccentric strap 35 encircling an eccentric 36 fixed on shaft 33. Each pump is provided with an inlet valve 39 and a spring-closed outlet valve 40. While the engine is running in either direction, each upward thrust of the plunger 34 sucks oil into the pump, inlet valve 39 being lifted from its seat by the incoming oil, and, if the inlet valve is allowed to close thereafter, the downward thrust of the plunger 34 forces the oil into connection 38 and to the fuel-spray valve of the cylinder 80 served by the pump. On shaft 20 below each engine cylinder is fixedly mounted an eccentric 41 for co-operation with an eccentric strap 42 provided with a dependent arm 42'. In each fuel-pump, a valve-gear for 85 the inlet valve 39 is provided driven by the corresponding eccentric 36 and consisting of an offset arm 34' carried by plunger 34 and links 43 and 44; these links are pivoted to each other and link 43 is pivoted to the dependent arm 42' of the associated eccentric strap 42. This link 43 passes directly under the lower end of the stem 39' of the oil inlet valve 39.

With the parts arranged as shown in Fig. 16, the upward movement of the plunger 34 is accompanied by upward movement of link 43 and the link carries the inlet valve 39 with it. Also, as the plunger 34 moves downward, the link 43 and valve 39 move downward with it and the valve 39 reaches its seat just as the plunger reaches the limit of its downward movement. Such reciprocation of the plunger 34, therefore, would merely cause a surging of oil back and forth from the inlet pipe 37 past the valve seat to the chamber of the pump. This is the relation of the parts referred to when the needle valve 26 controlling the spray-air is in the position for closing the passage 110 from inlet pipe 28 to the pipe 27 supplying the spray valves, and at such time the eccentric 41 and arm 42' operated thereby are in their highest position. If the shaft 20 were turned so as to rotate the sector 25 115 in the direction of the arrow 25' on Fig. 16, this would operate to open the air valve 26 and to lower the arm 42', and the end of the link 43 which is connected to arm 42'. Link 43 would thus be carried a short dis- 120

tance downward from the foot 39' of the inlet valve 39. Under such conditions, the upward movement of plunger 34 would act to draw oil into the chamber of the pump through the inlet pipe 37, raising the inlet valve 39 from its seat. During the course of the upward movement of plunger 34, the link 43 would engage the foot 39' of the inlet valve 39. Then the plunger 34 would start downwardly carrying the link 43 downward with it and at an intermediate point in the downward movement of plunger 34 the link 43 would be lowered to such extent as to permit the valve 39 to reach its seat. Thus the exit of oil from the chamber of the pump into the inlet 37 would be closed and the remainder of the downward movement of the plunger 34 would force oil out through the outlet 38, the pressure of the oil serving to raise the outlet valve 40 from its seat. If the shaft 20 were turned through 180°, the spray-air valve 26 would be opened wide and the arm 42' would be lowered to its lowermost position. Under such circumstances, the reciprocation of link 43 in correspondence with the reciprocation of plunger 34 would not carry the link 43 into engagement with the foot of the inlet valve 39 at all or at least would not serve to hold the inlet valve off its seat. Under such conditions, the inlet valve 39 would be raised from its seat by the incoming oil during an upward movement of plunger 34 and immediately upon the plunger 34 starting downward, the pressure of the oil would re-seat valve 39 so that the valve would be closed during practically the whole of the downward movement of the plunger 34 and the maximum amount of oil would be pumped out from the chamber of the pump into the outlet pipe 38 by the downward movement of plunger 34.

Thus, by the operation of a single controller, namely, the fuel hand-wheel 21, the amount of fuel-oil and the amount of spray-air supplied to the fuel-spray valves of the engine is automatically and simultaneously regulated so that the air and oil are supplied in the proper proportions at all times, and this is true although all of the fuel-pump plungers are reciprocated continuously during operation of the engine. By the manipulation of this single controller, the supply of spray-air and fuel-oil to the inlet valves of the engine may be cut off entirely or may be increased to the maximum or may be adjusted to any intermediate point in order to cause the engine to develop the amount of power desired and at all times the desired proportion of the two ingredients is maintained.

In order to prevent a careless or nervous operator from actuating the fuel hand-wheel 21 to open needle-valve 26 and thus feed spray-air and oil to the cylinder fuel-

spray valves while the main hand-wheel 19 is in its "stop" position, when the cylinder vent valves are open, a mechanical interlock is provided as shown in Fig. 7.

Hand-wheel 21 is provided with a recess 21' to cooperate with the adjacent end of a detent 23' slidably mounted in a housing 23" mounted upon frame 23; the opposite end of the detent abuts against a lug 19" on main hand-wheel 19 when the main hand-wheel is in its "stop" position. Detent 23' is spring-urged as indicated so that even when the lug 19" on the main hand-wheel 19 is moved away from the detent, said detent acts as an impositive catch to hold the fuel hand-wheel in its no-feed position; however, this impositive catch becomes positive, and an absolute lock, when the main hand-wheel is in its "stop" position.

The means just described is useful also to serve another end. When main hand-wheel 19 has been rotated in either direction to close the control valve 6 and thus close the cylinder vent-valves (Fig. 6), and when fuel hand-wheel 21 has been rotated (Fig. 7) to open needle-valve 26 (Fig. 16), a return of hand-wheel 19 to its "stop" position and a consequent opening of the vent-valves is precluded. It is necessary to first move the hand-wheel 21 to its normal or "stop" position and thus close the needle-valve 26 and discontinue the operation of the feed pumps 34. Otherwise, of course, an undesirable loss of spray-air would occur through the cylinder vent-valves. It will be seen from Fig. 6 that, no matter in which direction main hand-wheel 19 has been rotated from its "stop" position, it will be impossible to return the wheel to that position while the fuel hand-wheel 21 is removed from its stop position. This is due to the fact that with the fuel hand-wheel removed from its stop position, detent 23' is out of recess 21' and therefore the inner end of the detent lies in the path which lug 19" would have to traverse in moving main hand-wheel 19 back to its "stop" or cylinder-venting position.

The pneumatic control system forming the present invention also involves as an important feature thereof the provision of a pneumatic interlock adapted to prevent the possibility of feeding starting air and fuel-oil simultaneously to any one of the cylinders. It has been explained that, according to the present arrangement, in starting either group of cylinders on air, whether ahead or astern, control valve 5 is opened to actuate relay valve 15' to feed starting-air to the air-starting valves of the selected group, only when one of the control valves 2, 4, 1 and 3 is simultaneously opened to set the air-starting valves of the A cylinders for ahead running, the air-starting valves of said A cylinders for astern running, the

air-starting valves of the B cylinders for ahead running, or the air-starting valves of said B cylinders for astern running. When the relay valve 15^a (Fig. 6) is opened, starting-air is fed to the air-starting valves of all the cylinders. Therefore, the pneumatic interlock means includes two separate pneumatic interlocks for each cylinder group A and B, one of these being connected with the astern air-starting control and the other with the ahead air-starting control. Referring to Figs. 6, 16 and 17, associated with each pump A and B are a plurality of chambers 45 and 46. A pair of such chambers is shown in section in Fig. 16, from which it will be seen that each chamber 45 is provided with a movable piston 45' and each chamber 46 is provided with a movable piston 46'. As to each pump, the pair of pistons is normally arranged as indicated. The pistons of the pair are fixedly connected by a rod 45", and piston 46' carries fixedly an upstanding reduced extension 46". As shown best in Fig. 17, above the top of its chamber 46, each extension 46" is forked and the tips of the fork-tines are adapted to engage the foot 39' on the stem of the associated pump's inlet valve 39 when that valve is in the closed position.

Referring to Figs. 6 and 16, it will be noted that the pipes 12, 14, 11 and 13 are provided with branch connections 12', 14', 11' and 13'. Pipes 12' and 14' lead to the chambers 45 and 46, respectively, of the oil-feeding mechanisms of the cylinders of the A group; and pipes 11' and 13' lead to the chambers 45 and 46, respectively, of the cylinders of the B group. Due to the presence of these branch connections, the instant control valve 2 is opened to set the ahead controls for the air-starting valves of the A group of cylinders, compressed air is admitted to the chamber 45 of each of the A' pumps below the pistons 45' in those chambers to raise those pistons and lift the inlet valve 39 of each of the A' pumps off its seat; the instant control valve 4 is opened to set the astern controls for the air-starting valves of the A group of cylinders, compressed air is admitted to the chamber 46 of each of the A' pumps below the pistons 46' in those chambers to raise those pistons and lift the inlet valve 39 of each of the A' pumps off its seat; the instant control valve 1 is opened to set the ahead controls for the air-starting valves of the B group of cylinders, compressed air is admitted to the chamber 45 of each of the B' pumps below the pistons 45' in those chambers to raise those pistons and lift the inlet valve 39 of each of the B' pumps off its seat; and the instant the control valve 3 is opened to set the astern controls for the air-starting valves of the B group of cylinders, compressed air is ad-

mitted to the chamber 46 of each of the B' pumps below pistons 46' in those chambers to raise those pistons and lift the inlet valve 39 of each of the B' pumps off its seat. Thus, whenever either group of cylinders is set for running ahead or astern on starting-air, the fuel-pumps serving the fuel-spray valves of that group are rendered ineffective, since the reciprocations of plungers 34 of the fuel-pumps last mentioned do nothing more than cause the oil-fuel to surge back and forth past the inlet valves 39 of said pumps.

In this connection, it should be noted that if the oil-fuel fed to the connection 37 (Fig. 6) comes, as would be desirable, from a gravity tank, the tank should be so located that the head of the fuel-flow is not sufficient to overcome the resistance to compression of the expansible springs illustrated as normally urging the outlet valves 40 of the pumps to their seats (Fig. 16).

The detached diagrammatic view associated with Fig. 6 indicates the positions of the valves on each cylinder and gives the function of each valve. In the middle is the valve by which the compressed air is admitted to the cylinder for starting. Next above this is the control valve by which the starting valve is set for running ahead. Next above this is the control valve by which the starting valve is set for running astern. Below the starting valve is the fuel-spray valve and next below this is the relief valve.

The operation of the engine may be briefly summarized as follows: With the main hand-wheel 19 at "stop," control valve 6 (Fig. 6) is open, and air is fed to connection 16 to open all cylinder vent-valves. To run ahead, the main hand-wheel 19 is moved in the appropriate direction to the first running position. Control valve 6 (Fig. 6) closes and therefore all cylinder vent-valves close. Then fuel hand-wheel 21 (Fig. 6) is rotated to open needle-valve 26 (Fig. 16), so that a moderate amount of spray-air is fed into connection 27 (Fig. 6) and to all the cylinder fuel-spray valves, and so that the throw of link 43 (Fig. 16) is adjusted accordingly. The main hand-wheel 19 is then moved on to the second position, whereupon control valves 5 and 2 (Fig. 6) open. Air therefore flows into connection 15 and actuates relay valve 15^a, so that starting air is fed through connection 15^b to all cylinder air-starting valves. On the opening of control valve 2, air flows through connection 12 to set the ahead-controls for the air-starting valves of the A cylinders, and the starting-air in connection 15^b is free to enter the A cylinders through the starting valves thereof at the proper times in the operation of the engine to cause reciprocation of the pistons in the A cylinders for ahead-drive of the engine shaft.

If now the crank-angles are favorable, and the resistance to turning movement not too great, the engine will start in the ahead direction. At the same time, the plungers of pumps B' will be effective to send oil-fuel to the B cylinders; while the plungers of pumps A' will be ineffective thus to serve the air-driven A cylinders, due to the fact that air in the branches 12' of connection 12 (Fig. 6) acts against the underside of piston 45' (Fig. 16) of each A' pump and thereby causes the forked end of the associated extension 46^a (Fig. 17) to lift and hold the inlet valve 39 of each A' pump off its seat. As soon as the engine starts running, and has been running long enough for the B cylinders to get under fuel-drive, the main hand-wheel 19 is brought back to the "first position", thereby closing control valves 5 and 2. The closing of the valve 5 shuts off the supply of starting-air to connection 15^b; and the closing of valve 2 exhausts the connections 12 and 12'. The exhaustion of connection 12 takes the air-starting valves of the A cylinders off their ahead-setting, and the exhaustion of connection 12' permits the piston 45' of each A' pump to return to locations similar to the location of the piston 45' of Fig. 16, so that the inlet valves 39 of said A' pumps are no longer held off their seats but are raised and lowered periodically by the links 43 to render effective the A' pumps. In a second or two, therefore, the B cylinders, and hence all cylinders, will be running on fuel. And then fuel hand-wheel 21 may be rotated so as to bring the engine up to speed, gradually or rapidly as desired.

If, however, conditions are such that with the main hand-wheel in its "second position", the engine does not start, then the main hand-wheel is brought to the third position whereupon control valve 1 (Fig. 6) opens. Air therefore flows through connections 11 to set the ahead controls for the air-starting valves of the B cylinders, and the starting air in connection 15^b is admitted to the B cylinders at the proper times to operate the engine in the ahead direction. As soon as air flows into connection 11, its consequent flow into branches 11' (Fig. 6) causes it to act against the underside of the piston of each B' pump similar to the piston 45' of Fig. 16 and thus causes the forked end of the associated extension 46^a to lift and hold the inlet valve of each B' pump off its seat, so that while the B cylinders are running on air, fuel is not fed to them.

Therefore, at this "third position" adjustment of main hand-wheel 21, the engine must start in the desired direction. Thereafter, the main hand-wheel is returned to its "second position", thus taking the B cylinders off air and feeding fuel thereto, and

then to its "first position", thus taking the A cylinders off air and feeding fuel thereto also; whereupon, with the engine running as to all cylinders on fuel, the fuel hand-wheel may be rotated so as to bring the engine up to speed gradually or rapidly as desired.

To stop the engine, the wheel 21 controlling the fuel supply is moved to the position for discontinuing the supply of spray-air and oil to the engine and then the wheel 19 is moved to the mid-position in which all the control valves 1, 2, 3, 4 and 5 are closed and the control valve 6 is opened to vent all cylinders.

To run the engine astern, the hand-wheel 19 is moved in the opposite direction from the mid-position to the first or running position, thereby closing control valve 6, and effecting the closure of all cylinder vent valves. Then the fuel hand-wheel 21 is positioned as above described and the main hand-wheel 19 is moved to the second position. This opens the control valves 4 and 5 and air is admitted to the A cylinders at the times appropriate for running the engine in the astern direction. Also, the fuel pumps of the A cylinders are rendered inoperative by air supplied to their chambers 46 through pipes 14'. If the engine fails to start under these conditions, the hand-wheel 19 is moved on to the third position for admitting air to all cylinders and rendering the pumps of all cylinders inoperative as above described.

At this astern "third position" adjustment of main hand-wheel 21, the engine must start in the desired direction. Then the main hand-wheel is returned to its astern "second position", thus taking the B cylinders off air and feeding fuel thereto, and then to the astern "first position", thus taking the A cylinders off air and feeding fuel thereto also. Then, with the engine running astern with all its cylinders on fuel, the fuel hand-wheel 21 may be rotated so as to bring the engine up to speed gradually or rapidly as desired.

Fig. 18 illustrates a construction of the type shown in the other figures adapted for use in connection with a pneumatically actuated reversing mechanism whereby the cams of the engine are shifted from one position to another to adapt the engine for operation in one direction or the other. Also the Fig. 18 construction includes distributors driven from the engine shaft and operating to direct compressed air to one cylinder after another in succession in starting the engine.

The pneumatically actuated reversing mechanism is indicated at 56 consisting of a cylinder and a piston 56^a therein, the piston being connected to devices for shifting the cams of the engine from positions for

operating the engine in one direction to positions for operating the engine in the reverse direction. The piston 56^a controls an outlet port leading from the cylinder so that compressed air entering cylinder 56 at either port 56^c or port 56^d first actuates the piston 56^a to effect reversal and then flows through port 56^e.

Two distributors, one for each group of 10 cylinders, are shown diagrammatically at C'' and D''. Each is driven from the engine shaft and each distributes compressed air for starting to the cylinders of the corresponding group in succession.

15 Control-box 57 includes five normally closed control valves 1, 2, 3, 4 and 5, a conduit 58 for feeding compressed air to the control valves, and within the control-box a main passage 58' and suitable branch passages as indicated leading from the main passage and each having interposed therein one of the control valves 1, 2 and 5. The valves 3 and 4 are interposed in an auxiliary passage 53'' isolated from main passage 58' as indicated. Leading from control valve 1 to inlet port 56^c is a connection 51'. Leading from control valve 2 to inlet port 56^d is a connection 52'. Leading from outlet port 56^e to auxiliary passage 53'' is a connection 53'. Thus, opening control valve 3 or 4 will be ineffective to permit flow of air to the corresponding distributor C'' or D'' until control valve 1 or 2 has first been opened, either to send air immediately into connection 53' or else first to actuate the piston of the reversing cylinder 56 and then send air into connection 53'. A branch connection 53^a leads from connection 53' to a relay valve 15^a similar to the relay valve 15^a of Fig. 1; so that as soon as the reversing cylinder has been actuated, if necessary, to set the adjustable parts of the engine for running in the desired direction, the relay valve opens a normally closed air-starting line 53^b leading to all the cylinder air-starting valves. And then only may valve 3 or 4 become effective to feed air to its associated connection 53^c or 53^d when such valve 3 or 4 is opened.

50 Leading from control valve 5 is a connection 55' which goes to all cylinder vent-valves.

Connection 53^e leads to the C'' distributor, serving, as indicated at C^a, the controls for the air-starting valves of the C cylinders, and connection 53^d leads to the D'' distributor, serving, as indicated at D^a, the controls for the air-starting valves of the D cylinders. Thus, according as control valve 3 or 4 is opened immediately following an opening of control valve 1 or 2, the opening of either of which instantly actuates the relay valve 15^a, either the C cylinders or the D cylinders are air-started to cause running of the engine in the desired direction.

In the construction shown in Fig. 18, it is desirable to render ineffective the plungers of the C' or D' fuel-pumps according as the C or D cylinders are running on air. Therefore a branch connection C^b leads from 70 the connection 53^e serving the C'' distributor, and a branch connection D^d leads from the connection 53^d serving the D'' distributor; the former branch connection leads to locking cylinders 46^a associated with the 75 C' fuel-pumps, and the latter branch connection leads to locking cylinders 46^b associated with each of the D' fuel-pumps. Each of these locking cylinders 46^b may be of the construction illustrated at 46 in Fig. 80 16, except that the rod 45^a in Fig. 16 may be dispensed with. The shaft 33 may, like the shaft 33 of Fig. 6, be driven by the engine-shaft.

The operation of the construction just described, in brief, is as follows: Whether or not a hand-wheel similar to the hand-wheel 19 of Fig. 16 be provided, the five control valves of Fig. 18 are designed to be actuated in various predetermined orders which may 85 be expressed by saying that were the hand-wheel 19 of Fig. 16 employed, it would have a mid or "stop" position, four positions to one side of the "stop" position for ahead running and four positions to the other side 90 of the "stop" position for astern running. With the hand-wheel in the stop position, the control valve 5 is open and all cylinders are vented. For running ahead, the wheel is moved to the first position closing control 100 valve 5 and all vents. Then the hand-wheel is turned to the next position, opening the control valve 1 and admitting air to cylinder 56 to force piston 56^a downward and connect pipes 51' and 53' so as to admit air 105 to connection 53'' and relay valve 15^a which valve opens the air-starting line 53^b. The handle is then moved on to the next position to open control valve 3. This actuates distributor C'' to feed starting air to the C cylinders and render the C' fuel pumps ineffective. The engine may start under these 110 conditions but if not, the hand-wheel is moved on to the next position, opening control valve 4. This actuates the distributor 115 D'' to feed starting air to the D cylinders and render the D' fuel-pumps ineffective.

Thereafter, the hand-wheel is moved backward to run first the D cylinders and then all cylinders on fuel supplied by the C' and 120 D' pumps.

To run the engine in the opposite direction, the same procedure is followed except that the control valve 2 is opened instead of the control valve 1 and when air passes 125 from valve 2 through pipe 52' to the cylinder 56, it first actuates the piston in the cylinder and then flows out through pipe 53'.

It will be noted that the construction above described includes a means for con- 130

trolling the spray-air and fuel together to control the speed of the engine, and the making of all other controls on the engine pneumatic and operated from a single hand-wheel. Hence the operator manipulates only two hand-wheels to start, stop, reverse and control the speed of the engine, and fuel and starting-air cannot be turned onto the same cylinder at the same time. The construction is such as to insure a smooth, even, positive starting of the engine even though the operator is not experienced in the handling of the engine, or does not observe proper care, and furthermore, the apparatus is economical in the use of starting-air.

It should be understood that while each of the systems above described is arranged for a cylinder group control in which two groups of cylinders are provided, similar systems come within the scope of the invention when designed so as to be applicable to any number of cylinders per engine and any number of groups of cylinders and with one or more cylinders per group. In each of such cases, when the system is like that of Fig. 1 or 6, the control-box or the like will preferably be provided with a number of control valves equal to twice the number of cylinder groups plus two, and when the system is like that of Fig. 18 the control-box or the like will preferably be provided with a number of control valves equal to the number of cylinder groups plus three.

We claim:

1. In a multi-cylinder heavy oil internal combustion engine, the combination of a first cylinder, a second cylinder, starting-air supply means for the first cylinder, starting-air supply means for the second cylinder, and controlling means for the two supply means actuatable to start the engine from idle condition by causing the admission of starting-air to one cylinder without admitting it to the other, and then to cause the admission of starting-air to the other cylinder.

2. In a multi-cylinder heavy oil internal combustion engine, in combination, a first cylinder, a second cylinder, normally ineffective starting-air supply means for each of the cylinders, normally ineffective fuel supply means for each of the cylinders, a normally closed vent-valve for each cylinder, and a separately actuatable pneumatic control for each of the four supply means and for all the vent-valves.

3. In a multi-cylinder heavy oil internal combustion engine, in combination, a first cylinder, a second cylinder, an air-starting valve on each cylinder, a common conduit for feeding starting-air to each of said air-starting valves, a setting means associated with each air-starting valve and operable to set its said valve for ahead or reverse air-starting of the engine, fuel supply means for each of the cylinders, and pneumatic con-

trolling mechanism for said setting means capable of operating the setting means of one cylinder without affecting that of the other cylinder.

4. In a multi-cylinder heavy oil internal combustion engine, in combination, a first cylinder, a second cylinder, an air-starting valve on each cylinder, a common normally closed conduit for feeding starting-air to each of said air-starting valves, a setting means associated with each air-starting valve and operable to set its said valve for ahead or reverse air-starting of the engine, fuel supply means for each of the cylinders, pneumatic controlling mechanism for said setting means capable of operating the setting means of one cylinder without affecting that of the other cylinder, and a controlling mechanism for said common conduit adapted to open the conduit when either air-starting valve has been set.

5. In a multi-cylinder heavy oil internal combustion engine, in combination, a number of cylinder groups one cylinder of each of said groups having a normally open vent-valve, an air-starting valve and normally ineffective setting means for the air-starting valve adjustable to set said air-starting valve for ahead or reverse air running of the engine, a normally closed common starting-air supply-conduit serving all said air-starting valves, and pneumatic control means for the engine including air connections and a normally open control valve and a plurality of normally closed control valves interposed in said connections, the normally open control valve when closed causing a closing of all the vent-valves, and of the normally closed control valves one when opened making one of said setting means effective as to ahead rotation of the engine, one when opened making said setting means effective as to astern rotation of the engine, one when opened making another of said setting means effective as to ahead rotation of the engine, one when opened making the last-mentioned setting means effective as to astern rotation of the engine, and one when opened causing an opening of said common conduit.

6. In a multi-cylinder heavy oil internal combustion engine, in combination, a first cylinder, a second cylinder, normally ineffective starting-air supply means for each of the cylinders, normally ineffective fuel supply means for each of the cylinders, independent controls for the starting air supply means of the cylinders one of the controls being manually actuatable when the engine is stationary to render effective the starting-air supply means of its cylinder only and a separate control associated with the fuel supply means of each cylinder automatically set to render ineffective the fuel supply means of a cylinder when one of said manu-

- ally actuatable controls is actuated to render effective the starting-air supply means of that cylinder.
7. In a multi-cylinder, reversible internal combustion engine, the combination of a first cylinder, a second cylinder, normally ineffective starting-air supply means for each of the cylinders, normally ineffective fuel supply means for each of the cylinders, a separate starting-air control for each cylinder, a separate fuel control for each cylinder, an interlock associated with each cylinder and with the two controls therefor whereby while starting-air is being fed to either cylinder the fuel supply means for that cylinder is automatically maintained ineffective, a controller for stopping the engine and starting it in a reverse direction, and means for preventing stopping of the engine and starting it in the reverse direction when fuel is being fed to the cylinders.
8. In a multi-cylinder heavy oil internal combustion engine, in combination, a number of cylinders divided into a number of 25 separately operable units, a vent-valve for each cylinder, an air-starting valve for each cylinder, an astern setting means for each cylinder's air-starting valve and an ahead setting means for each cylinder's air-starting 30 valve, a fuel-spray valve for each cylinder, and a plurality of independently actuated pneumatic controls for said valves and said ahead and astern setting means, there being at least twice as many such pneumatic 35 controls as the number of said separately operable units.
9. In a multi-cylinder heavy oil internal combustion engine, in combination, a number of cylinders divided into a number of 40 separately operable units, a vent-valve for each cylinder, an air-starting valve for each cylinder, an astern setting means for each cylinder's air-starting valve and an ahead setting means for each cylinder's air-starting 45 valve, a fuel-spray valve for each cylinder, and a plurality of independently actuated pneumatic controls for said valves and said ahead and astern setting means, there being as many of such pneumatic controls 50 as twice the number of said separately operable units plus two.
10. In a multi-cylinder heavy oil internal combustion engine, in combination, a number of cylinders divided into a number of 55 separately operable units, a vent-valve for each cylinder, an air-starting valve for each cylinder, an astern setting means for each cylinder's air-starting valve, a fuel-spray valve for each cylinder, a plurality of independently actuated pneumatic controls for said valves and said ahead and astern setting means, there being at 60 least twice as many such pneumatic controls as the number of said separately operable
- units, and a hand-wheel and mechanical instrumentalities for predeterminedly operating said pneumatic controls and controlled by the rotation of said hand-wheel.
11. In a multi-cylinder heavy oil internal 70 combustion engine, in combination, a number of cylinders divided into a number of separately operable units, a vent-valve for each cylinder, an air-starting valve for each cylinder, an astern setting means for each 75 cylinder's air-starting valve and an ahead setting means for each cylinder's air-starting valve, a fuel-spray valve for each cylinder, a plurality of independently actuated pneumatic controls for said valves and said setting means, there being as many of such pneumatic controls as twice the number of 80 said separately operable units plus two, a plurality of mechanical instrumentalities each for operating one of said controls, and a hand-wheel rotatable in either direction 85 from a normal set, the hand-wheel in its normal set causing one of said pneumatic controls to open all the vent-valves, the hand-wheel when rotated in one direction 90 from its normal set being adapted first to actuate one of said pneumatic controls to close said vent-valves, next to actuate one of said pneumatic controls to set to effectiveness the ahead setting means of all cylinders 95 in one of said units and next to actuate one of said pneumatic controls to set to effectiveness the ahead setting means of all the cylinders in another of said units, and the hand-wheel when rotated in the opposite 100 direction from its normal set being adapted first to actuate one of said pneumatic controls to close said vent-valves, next to actuate one of said pneumatic controls to set to effectiveness the astern setting means of one 105 of said units and next to actuate one of said pneumatic controls to set to effectiveness the astern setting means of another of said units.
12. In a multi-cylinder heavy oil internal 110 combustion engine, in combination, a number of cylinders divided into a number of separately operable units, selectively operable means for starting the engine from idle condition by first supplying starting-air to the cylinders of one of the units and 115 then to the cylinders of a plurality of the units, means for supplying fuel to the cylinders of one or more of said units as desired, and an interlock to prevent the simultaneous supply of starting-air and fuel 120 to any one cylinder.
13. In a multi-cylinder heavy oil internal 125 combustion engine, in combination, a number of cylinders divided into a number of separately operable units, selectively operable means for supplying starting-air to the cylinders of one or more of said units, means for supplying fuel to all the cylinders in said units, a normally ineffective pneumatically operated interlock to prevent the si- 130

multaneous supply of starting-air and fuel to any one cylinder, a normally closed air-line for rendering effective said interlock when the air-line is opened, and means for opening said air-line whenever said selectively operable means is operated.

14. In a multi-cylinder heavy oil internal combustion engine, in combination, a number of cylinders divided into a number of
10 separately operable units, selectively operable means for supplying starting-air to the cylinders of one or more of said units, means for supplying fuel to all the cylinders in said units and including a separate fuel-pump for each cylinder driven continuously by the engine during rotation thereof in either direction, a separate normally ineffective pneumatically actuated interlock associated with each fuel-pump, a normally
15 closed air-line associated with each interlock for rendering the latter effective when its air-line is opened, and means for opening the air-line serving the interlock for a fuel-pump of a particular cylinder when said
20 selectively operable means is operated to supply starting-air to that cylinder.

15. In a multi-cylinder heavy oil internal combustion engine, in combination, a number of cylinders divided into a number of 30 separately operable units, a first adjustable controller and means associated therewith whereby said controller in one adjustment starts one of said units on air for ahead running of the engine, in another adjustment starts the other of said units on air for ahead running of the engine, in another adjustment starts one of said units for astern running of the engine and in another adjustment starts the other of said units for 35 astern running of the engine, and a second controller and means associated therewith for feeding spray-air to all the cylinders.

16. In a multi-cylinder heavy oil internal combustion engine, in combination, a number of cylinders divided into a number of separately operable units, a first adjustable controller and means associated therewith whereby said controller in one adjustment starts one of said units on air for ahead running of the engine, in another adjustment starts the other of said units on air for ahead running of the engine, in another adjustment starts one of said units for astern running of the engine and in another adjustment starts the other of said units for astern running of the engine, and a second controller and means associated therewith for feeding oil-fuel to all the cylinders.

17. In a multi-cylinder heavy oil internal
60 combustion engine, in combination, a number
of cylinders divided into a number of
separately operable units, a first adjustable
controller and means associated therewith
whereby said controller in one adjustment
85 starts one of said units on air for ahead

running of the engine, in another adjustment starts the other of said units on air for ahead running of the engine, in another adjustment starts one of said units for astern running of the engine and in another adjustment starts the other of said units for astern running of the engine, and a second controller and means associated therewith for feeding spray-air to all the cylinders and for simultaneously feeding oil-fuel to all the cylinders. 70 75

18. In a multi-cylinder heavy oil internal combustion engine, in combination, a number of cylinders divided into a number of separately operable units, a first adjustable controller and means associated therewith whereby said controller in one adjustment starts one of said units on air for ahead running of the engine, in another adjustment starts the other of said units on air for ahead running of the engine, in another adjustment starts one of said units on air for astern running of the engine and in another adjustment starts the other of said units on air for astern running of the engine, a second adjustable controller, spray-air feeding means for all the cylinders, oil-fuel feeding means for all the cylinders, means controlled by the second controller adapted at each adjustment of the latter to adjust said spray-air feeding means predeterminedly, and means simultaneously controlled by the second controller for adjusting said oil-fuel feeding means so that an amount of oil-fuel will be fed to each cylinder in proper proportion to the amount of spray-air fed thereto.

19. In a multi-cylinder heavy oil internal combustion engine, in combination, a first group of cylinders, a second group of cylinders, pneumatic engine-handling means including a plurality of selectively actuatable control-valves, compressed-air inlet valves on the cylinders controlled by the control-valves, and a manually rotatable shaft carrying cams each of which actuates one of said control-valves in a predetermined angular adjustment of said shaft. 11

20. In a multi-cylinder heavy oil internal combustion engine, in combination, a first group of cylinders, a second group of cylinders, pneumatic means including a plurality of control valves and a manually actuatable controller therefor for venting all cylinders and for running one or both groups on air, a manually actuatable controller operable for feeding fuel-spay to either group while the other group is running on air, and a cam-shaft rotatable by the first-mentioned controller and carrying cams each of which actuates one of said control-valves in a pre-determined angular adjustment of said shaft, said shaft having a predetermined angular set to stop the engine. 11 12

21. In a multi-cylinder heavy oil internal 13

- combustion engine, in combination, a first group of cylinders, a second group of cylinders, pneumatic means including a plurality of control valves and a selectively manipulable controller therefor for venting all the cylinders and for running one or both groups in either direction on air, pneumatic means and a selectively manipulable controller therefor for feeding fuel-spray to either group while the other is running on air in either direction, and a cam-shaft rotatable by the first-mentioned controller and carrying cams each of which actuates one of said control-valves in a predetermined angular adjustment of said shaft, said shaft having a predetermined angular set to vent the cylinders and thus stop the engine after the same has been running in either direction, said set being between an angular adjustment of the shaft which causes one group to run ahead on air and an angular adjustment of the shaft which causes the group last-mentioned to run astern on air, whereby in reversing the engine all the cylinders must surely be vented before starting the engine in the new direction.
22. In a multi-cylinder heavy oil internal combustion engine, in combination, a plurality of normally closed control valves each interposed in a connection adapted to have compressed air fed thereto beyond the interposed valve thereof when said valve is opened, one of said connections when its valve is opened causing a feeding of compressed air to the air-starting valves of all the cylinders, a flow of air in another of said connections beyond the interposed valve causing the air-starting valves of certain of the cylinders to be set for ahead running of the engine, a flow of air in another of said connections beyond the interposed valve causing the air-starting valves of the cylinders last mentioned to be set for astern running, a flow of air in another of said connections beyond the interposed valve causing the air-starting valves of certain of the other cylinders to be set for ahead running, a flow of air in another of said connections beyond the interposed valve causing the air-starting valves of the last-mentioned cylinders to be set for astern running, and a flow of air in another of said connections causing all the cylinders to be vented, said control valves being grouped; and a selectively manipulable single controller variously adjustable to open all of said control valves.
23. In a multi-cylinder heavy oil internal combustion engine, in combination, a plurality of normally closed control valves each interposed in a connection adapted to have compressed air fed thereto beyond the interposed valve thereof when said valve is opened, one of said connections when its valve is opened causing a feeding of compressed air to the air-starting valves of all the cylinders, a flow of air in another of said connections beyond the interposed valve causing the air-starting valves of certain of the other cylinders to be set for ahead running, a flow of air in another of said connections beyond the interposed valve causing the air-starting valves of certain of the other cylinders to be set for astern running, and a flow of air in another of said connections causing all the cylinders to be vented, said control valves being grouped; and a selectively manipulable single controller variously adjustable to open all of said control valves.
24. In a multi-cylinder heavy oil internal combustion engine, in combination, a plurality of cylinders, pneumatic means for handling the engine and including a control-box having a plurality of separately operable pneumatic control valves one for venting the engine and one for running said cylinders on air, and mechanical means adjacent to the box and selectively manipulable to operate various ones of said control valves.
25. In a multi-cylinder heavy oil internal combustion engine, in combination, pneumatic means for handling the engine during air-starting and while running on air, a first selectively adjustable controller for controlling said pneumatic means, oil-fuel and spray-air feeding means, a second selectively adjustable controller for controlling said feeding means, said first controller in one adjustment thereof venting the cylinders and said second controller in one adjustment thereof shutting off the supply of oil-fuel, and an interlock between said two controllers adapted to prevent the first controller being brought to its adjustment for venting the cylinders until the second controller is brought to its adjustment for shutting off the supply of oil-fuel.
26. In a multi-cylinder heavy oil internal combustion engine, in combination, pneumatic means for handling the engine during air-starting and while running on air, a first selectively adjustable controller for controlling said pneumatic means, oil-fuel and

- spray-air feeding means, a second selectively adjustable controller for controlling said feeding means, said first controller in one adjustment thereof venting the cylinders and said second controller in one adjustment thereof shutting off the supply of oil-fuel, and an interlock between said two controllers to prevent the second controller from being removed from its adjustment for shutting off the supply of oil-fuel until the first controller has been removed from its adjustment for venting the cylinders.
27. In a multi-cylinder heavy oil internal combustion engine, in combination, pneumatic control means for handling the engine for air starting including a normally inoperative pneumatically actuatable first device for venting the cylinders and including a normally inoperative pneumatically actuatable second device for starting the engine on air, a controller adjustable to a first position for rendering said first device operative to vent the cylinders and adjustable to a second position to render the said second device operative to start the engine, and means adapted to prevent the controller from being adjusted to its second position until the lapse of a predetermined interval of time after it is moved from its first position.
28. In a multi-cylinder heavy oil internal combustion engine, in combination, pneumatic control means for handling the engine for air starting including a pneumatically actuated first device for venting the cylinders and including a normally inoperative pneumatically actuated second device for starting the engine on air, said first device including an air connection leading to the cylinder vent valves, a controller movable to a first position for rendering said first device operative to vent the cylinders and movable to a second position to render the said second device operative to start the engine, and means including a normally ineffective detent connected to said air connection and pneumatically actuated to render it operative, said detent being located in the path which a part of the controller must traverse while being moved from its first to its second position to prevent the controller from being moved to its second position after leaving its first position until the vent valves of the cylinders are closed.
29. In a multi-cylinder heavy oil internal combustion engine, in combination, pneumatic control means for handling the engine for air starting including a pneumatically actuated first device for venting the cylinders, including a normally inoperative pneumatically actuated second device for starting the engine ahead on air and including a normally inoperative pneumatically actuated third device for starting the engine astern on air, a controller movable to a first position for rendering said first device operative to vent the cylinders, movable in one direction to a second position to render said second device operative to start the engine and movable in the opposite direction to a third position to render said third device operative to start the engine, and means adapted to prevent the controller from being moved to its second position or to its third position until the lapse of a predetermined interval of time after it is moved from its first position.
30. In a multi-cylinder heavy oil internal combustion engine, in combination, pneumatic control means for handling the engine for air starting including a pneumatically actuated first device for venting the cylinders, including a normally inoperative pneumatically actuated second device for starting the engine ahead on air and including a normally inoperative pneumatically actuated third device for starting the engine astern on air, a controller movable to a first position for rendering said first device operative to vent the cylinders, movable in one direction to a second position to render said second device operative to start the engine, and movable in the opposite direction to a third position to render said third device operative to start the engine, said first device including an air connection leading to the cylinder vent valves, and means for preventing the controller from being moved to its second position or to its third position until the lapse of a predetermined interval of time after moving it from its first position, said means including two normally ineffective detents pneumatically actuated to render them operative, one located in the path which a part of the controller must traverse while being moved from its first to its second position and one located in the path which a part of the controller must traverse while being moved from its first to its third position.
31. In a heavy oil internal combustion engine, the combination of two cylinders employed in starting the engine, and means for starting the engine from idle condition by starting one or both cylinders on air including a starting-air connection for serving one cylinder, a starting-air connection for serving the second cylinder and a manually operated controller for said starting-air connections movable from a neutral or non-operative position to a position for admitting air to one cylinder without admitting it to the other and then movable beyond the last-mentioned position to a position for admitting air to the two cylinders.
32. In a multi-cylinder heavy oil internal combustion engine, in combination, a connection for feeding spray-air to the fuel-spray valves of the cylinders, a normally closed air valve interposed in said connection, a fuel-pump having a suction plunger

and a mechanically actuated inlet valve, means whereby said plunger is driven during running of the engine, a fuel connection from the pump to a cylinder's fuel-spray valve, and an adjustable valve-gear for said inlet valve periodically operated during running of the engine and normally so adjusted that each operation thereof is ineffective to open the inlet valve, a single controller for said valve and means associated therewith and with said valve-gear whereby upon an adjustment of said controller to open the air-valve the valve-gear will be adjusted so that each operation thereof is effective to open the inlet valve.

33. In a multi-cylinder heavy oil internal combustion engine, in combination, a connection for feeding spray-air to the fuel-spray valves of the cylinders, a normally closed air valve interposed in said connection, a fuel-pump having a suction plunger and a mechanically actuated inlet valve, means whereby said plunger is driven during running of the engine, a fuel connection from the pump to a cylinder's fuel-spray valve, an adjustable valve-gear for said inlet valve periodically operated during running of the engine and normally so adjusted that each operation thereof is ineffective to open the inlet valve, and a single controller for said air valve and said valve-gear movable to simultaneously increase the extent to which the air-valve is opened and the extent of the effective opening of said inlet valve.

34. In an internal combustion engine, the combination of a plurality of cylinders including two groups of cylinders employed in starting the engine on compressed air, a controller having an operating handle which is movable to a stop position, a running position, a first starting position and a second starting position, means operated by a movement of the controller-handle from the stop position past the running position to the first starting position for admitting compressed air to the cylinders of one of said groups, and means operated by a continuation of the movement of the controller-handle to the second starting position for admitting compressed air to the cylinders of both of said groups.

35. In an internal combustion engine, the combination of a plurality of cylinders including two groups of cylinders employed in starting the engine on compressed air, a controller having an operating handle which is movable to a stop position, a running position, a first starting position and a second starting position, means operated by a movement of the controller handle from the stop position past the running position to the first starting position for admitting compressed air to the cylinders of one of said groups, means operated by a continuation of the movement of the controller handle to the second starting position for admitting compressed air to the cylinders of both of said groups.

movement of the controller handle to the second starting position for admitting compressed air to the cylinders of both of said groups, an individual fuel-pump corresponding to each cylinder and means for rendering each fuel-pump inoperative when compressed air for starting is admitted to the corresponding cylinder.

36. In an internal combustion engine, the combination of a plurality of cylinders including two groups of cylinders employed in starting the engine on compressed air, a controller having an operating handle which has a stop position and which is movable in either of two directions from the stop position, to a running position, a first starting position and a second starting position, means operated by a movement of the controller handle in either direction from the stop position past the running position, to the first starting position for admitting compressed air to the cylinders of one of said groups, and means operated by a continuation of the movement of the controller handle to the second starting position for admitting compressed air to the cylinders of both of said groups.

37. In an internal combustion engine, the combination of a plurality of cylinders including two groups of cylinders employed in starting the engine on compressed air, a controller having an operating handle which has a stop position and which is movable in either of two directions from the stop position to a running position, a first starting position and a second starting position, means operated by a movement of the controller handle in either direction from the stop position past the running position to the first starting position for admitting compressed air to the cylinders of one of said groups, means operated by a continuation of the movement of the controller handle to the second starting position for admitting compressed air to the cylinders of both of said groups.

38. In an internal combustion engine, the combination of a cylinder, a starting-valve thereon, a source of supply of compressed air, a connection from the source to the valve for carrying air which is admitted to the cylinder by the valve, a second air connection to the valve for carrying air adapted to set the valve for the admission of air to the cylinder to run the engine ahead, a third connection to the valve for carrying air adapted to set the valve for the admission of air to the cylinder to run the engine astern, valves in the first, second and third of said air connections, a controller, means

- operated by a movement thereof to one position for simultaneously opening the valves in the first and second of said air connections, and means operated by a movement of the controller to another position for simultaneously opening the valves in the first and third of said air connections.
39. In a multi-cylinder heavy oil internal combustion engine, in combination, a first cylinder, a second cylinder, starting-air supply means for each of the cylinders, fuel supply means for each of the cylinders, controlling means for setting the starting-air supply means for a cylinder, and pneumatically actuated means controlled by the supply of starting-air to a cylinder for rendering ineffective the fuel supply means of that cylinder.
40. In an internal combustion engine, the combination of a cylinder, a source of supply of compressed air from which spray-air is admitted to the cylinder, a pump having a reciprocating piston and an inlet valve, means for reciprocating the piston in accordance with the rotation of the engine shaft, means for opening the inlet valve periodically in accordance with the rotation of the engine shaft, and a single means for effecting an adjustment of the spray-air supplied to the cylinder and the time during which the inlet valve of the pump is held open by the operating mechanism thereof.
41. In an internal combustion engine, the combination of a cylinder, a piston therein, an engine shaft to which the piston is connected, a pneumatically actuated air-inlet valve on the cylinder, means for setting the air-inlet valve for operation of the engine ahead or astern at will, a pump operated in accordance with the rotation of the engine shaft and adapted to supply fuel to the cylinder, and pneumatic means associated with the air-inlet valve for rendering the pump ineffective when air is admitted to the cylinder for starting the engine.
42. In an internal combustion engine, the combination of a plurality of cylinders, a source of supply of compressed air, a controller having a mid position and movable in either direction from the mid position, means operated by the controller when in the mid position for venting the cylinders, means operated by a movement of the controller in one direction from the mid position for starting the engine in one direction, means operated by a movement of the controller in the other direction from the mid position for starting the engine in the reverse direction, and means for preventing too rapid movement of the controller from a position on one side of the mid position to a position on the opposite side of the mid position.
43. In an internal combustion engine, the combination of a plurality of cylinders, a controller having a mid position and movable in either direction from the mid position, means operated by the controller when moved in one direction from the mid position for starting the engine in one direction, means operated by a movement of the controller in the opposite direction from the mid position for starting the engine in the reverse direction, a controller movable to regulate the supply of fuel to the cylinders, and means for preventing movement of the first controller from a position on one side of the mid position past the mid position to the other side thereof when the second controller is in position for supplying fuel to the cylinders.
44. In an internal combustion engine, the combination of a plurality of cylinders, a controller, movable to a position for venting the cylinders, to a running position and to a position for supplying compressed air to the cylinders to start the engine, a second controller movable to regulate the supply of fuel to the cylinders, and means for preventing the movement of the first controller to the position for venting the cylinders when the second controller is in position to supply fuel to the cylinders.
45. In an internal combustion engine, the combination of a plurality of cylinders including two groups of cylinders employed in starting the engine on compressed air, a controller movable from a neutral position to a starting position for starting the engine from idle condition by supplying starting air to the cylinders of one group only and movable from that starting position either to a running position or to a second starting position for supplying starting air to the cylinders of both groups at will.
46. In an internal combustion engine, the combination of a plurality of cylinders including two groups of cylinders employed in starting the engine on compressed air, a controller movable from a neutral position to a starting position for starting the engine from idle condition by supplying starting air to the cylinders of one group only and movable from that starting position either to a running position or to a second starting position for supplying starting air to the cylinders of both groups at will, and means for supplying fuel to those cylinders of said groups which are not receiving the starting air.
47. In an internal combustion engine, the combination of a plurality of cylinders including two groups of cylinders employed in starting the engine on compressed air, a controller movable from a neutral position to a starting position for starting the engine from idle condition by supplying starting air to the cylinders of one group only and movable from that starting position either to a running position or to a second starting

position for supplying starting air to the cylinders of both groups at will, means for supplying fuel to each of the cylinders of the engine and means for rendering the fuel supply means of any cylinder inoperative when starting air is supplied to that cylinder, whereby when the engine is started by the admission of compressed air to either or both of said groups of cylinders the discontinuance of the supply of starting air to any cylinder causes fuel to be supplied to that cylinder.

48. In an internal combustion engine, the combination of a plurality of cylinders including two groups of cylinders employed in starting the engine on compressed air, a controller movable from a neutral position in either direction to a starting position for starting the engine from idle condition by supplying starting air to the cylinders of one group only for starting the engine in a direction corresponding to the direction of movement of the controller, the controller being movable from either of the said starting positions to either a running position or a second starting position, wherein compressed air is admitted to the cylinders of both groups to operate the engine in a direction corresponding to the direction of movement of the controller from the neutral position, and means for supplying fuel to the cylinders of the engine.

49. In an internal combustion engine, the combination of a plurality of cylinders including two groups of cylinders employed in starting the engine on compressed air, a controller movable from a neutral position in one direction to a first starting position for supplying starting air to the cylinders of one group only and movable farther in the same direction to a second starting position for supplying starting air to the cylinders of both groups, said controller being movable also to a running position in which the supply of starting air to the cylinders is discontinued, and means for supplying fuel to the cylinders of the engine.

50. In an internal combustion engine, the combination of a plurality of cylinders including two groups of cylinders employed in starting the engine on compressed air, a controller movable from a neutral position in one direction to a first starting position for supplying starting air to the cylinders of one group only and movable farther in the same direction to another position for supplying starting air to the cylinders of both groups, said controller being movable also to a running position which is located intermediate the neutral position and the first starting position and in which position the supply of starting air to the cylinders is discontinued, and means for supplying fuel to the cylinders of the engine.

51. In an internal combustion engine, the

combination of a plurality of cylinders including two groups of cylinders employed in starting the engine under compressed air, a controller movable from a mid position in one direction to one position for supplying starting-air to the cylinders of one group only and further in the same direction to another position for supplying starting-air to the cylinders of both groups for starting the engine in one direction and movable from the mid position in the opposite direction to one position for supplying starting-air to the cylinders of one group only and further in the same direction to another position for supplying starting-air to the cylinders of both groups for running the engine in the opposite direction, valve mechanism for the cylinders of the engine, means operated by movement of the controller for setting the valve mechanism for operation of the engine in the desired direction, and means for supplying fuel to the cylinders of the engine.

52. In an internal combustion engine, the combination of a plurality of cylinders including two groups of cylinders employed in starting the engine under compressed air, a controller movable from a mid position in one direction to one position for supplying starting-air to the cylinders of one group and to another position for supplying starting-air to the cylinders of both groups for starting the engine in one direction and movable from the mid position in the opposite direction to one position for supplying starting-air to the cylinders of one group and to another position for supplying starting-air to the cylinders of both groups for running the engine in the opposite direction, said controller having a running position on each side of its mid position in which running position the supply of starting-air to the cylinders of the engine is discontinued and means for supplying fuel to the cylinders of the engine.

53. In an internal combustion engine, the combination of a plurality of cylinders including two groups of cylinders employed in starting the engine under compressed air, a controller movable from a mid position in one direction to one position for supplying starting-air to the cylinders of one group and to another position for supplying starting-air to the cylinders of both groups for starting the engine in one direction and movable from the mid position in the opposite direction to one position for supplying starting-air to the cylinders of one group and to another position for supplying starting-air to the cylinders of both groups for running the engine in the opposite direction, said controller having a running position on either side of the mid position in which running position the supply of starting-air to the cylinders of the engine is discontinued,

- a valve mechanism for the cylinders of the engine, means operated by movement of the controller for setting the valve mechanism for operation of the engine in the desired direction, means for supplying fuel to the cylinders of the engine and means for precluding the supply of fuel to any cylinder when starting-air is being admitted to that cylinder.
54. In an internal combustion engine, the combination of a plurality of cylinders including two groups of cylinders employed in starting the engine under compressed air, a controller movable from a mid position in one direction to one position for supplying starting-air to the cylinders of one group and to another position for supplying starting-air to the cylinders of both groups for starting the engine in one direction and movable from the mid position in the opposite direction to one position for supplying starting-air to the cylinders of one group and to another position for supplying starting-air to the cylinders of both groups for running the engine in the opposite direction, said controller having a running position on either side of the mid position in which running position the supply of starting-air to the cylinders is discontinued, means for supplying fuel to the cylinders of the engine, and a second controller for regulating the supply of fuel.
55. In an internal combustion engine, the combination of a plurality of cylinders including two groups of cylinders employed in starting the engine under compressed air, a controller movable from a mid position in one direction to one position for supplying starting-air to the cylinders of one group and to another position for supplying starting-air to the cylinders of both groups for starting the engine in one direction and movable from the mid position in the opposite direction to one position for supplying starting-air to the cylinders of one group and to another position for supplying starting-air to the cylinders of both groups for running the engine in the opposite direction, said controller having a running position on either side of the mid position in which running position the supply of starting-air to the cylinders is discontinued, means for supplying fuel to the cylinders of the engine, a second controller for regulating the supply of fuel, and automatic means for precluding the supply of fuel to any cylinder when starting-air is being admitted to that cylinder.
56. In a multi-cylinder heavy oil internal combustion engine, the combination of a first cylinder, a second cylinder, starting-air supply means for the first cylinder, starting-air supply means for the second cylinder, controlling means for the two supply means whereby in starting the engine from idle condition starting-air may be admitted first to one cylinder without admitting it to the other and then to both cylinders, and means for admitting oil-fuel to one or both of the cylinders at will, such fuel admission means including fuel connections for the cylinders and a single manually operated controller operable during such starting of the engine to supply fuel to one cylinder when the starting-air controller is set to admit starting-air to the other cylinder and before the starting-air controller is set to admit starting-air to both cylinders.
57. In a heavy oil internal combustion engine, the combination of two cylinders employed in starting the engine, and means for starting one or both cylinders on air including starting-air connections for serving one or both cylinders at will and a manually operated controller for the starting-air connections movable in one direction from a neutral position directly to a position for admitting starting-air to one cylinder without admitting it to the other for ahead running of the engine and movable in the opposite direction from said neutral position directly to a position for admitting starting-air to one cylinder without admitting it to the other for astern running of the engine, said controller being also movable from either of said positions for admitting air to one cylinder directly to a running position in which the supply of starting air to the cylinders is discontinued.
58. In a multi-cylinder internal combustion engine, the combination of a first cylinder, a second cylinder, starting-air supply means for the two cylinders, and controlling means for the supply means including a controller adapted when the engine is idle to be moved from a neutral position in one direction to set the supply means to serve one cylinder without serving the other, thence to be moved in the same direction to set the supply means to serve both cylinders, and thence to be moved in the opposite direction to a position adjacent to the neutral position to set the supply means to serve one cylinder without serving the other.

In testimony whereof we affix our signatures.

GREGORY C. DAVISON.
JOHN W. ANDERSON.
